DRIER AND POLISHER FOR WOOD TURNINGS

Samuel R. Penney, Jr., Mechanic Falls, Maine, assignor to J. W. Penney & Sons Co., Mechanic Falls, Maine, a Corporation of Maine

Application February 14, 1931. Serial No. 515,809

1 Claim. (Cl. 34—5)

The invention forming the subject matter of this application is an apparatus designed for drying and polishing wood turning, such as clothes pins, dowel rods, broom handles and the like.

The main object of the invention is to provide an apparatus by which wood turning can be dried and polished thoroughly and uniformly in a comparatively short time, and so as to prevent warping of the turning and improve their appearance.

Other objects of the invention will become apparent as the detailed description thereof proceeds.

15 In the drawings:

Figure 1 is a central longitudinal section through a dryer forming this invention, parts thereof being shown in section and other parts in elevation.

20 Figure 2 is a vertical transverse section on the line 2—2 of Figure 1, the scale being enlarged.

Figure 3 is a fragmentary vertical section taken on the line 3—3 of Figure 2.

25 Figure 4 is a section taken on the line 4—4 of Figure 3; and

Figure 5 is a vertical transverse section taken on the line 5—5 of Figure 1.

As shown in the drawings, the apparatus comprises a large cylindrical drum 1, having supporting tracks 2 and 3 suitably secured thereto to ride on supporting rollers 4 and 5 which are suitably journaled in bearings 6 and 7, respectively, spaced apart on a supporting rail 8. Any desired number of these tracks and bearing rollers may be employed to support the drum rotatably upon a floor or platform 9. Two of these roller bearing constructions are illustrated in Figure 1.

40 One end of the drum has a ring gear 10 suitably secured thereto; and this gear meshes with a pinion 11 which is fixed to a shaft 12 journaled in bearings 13 and 14 at the upper ends of standards 15 and 16, respectively. One end of the shaft 12 has a bevel gear 17 secured thereto and meshing with a similar bevel gear 18 which is mounted on a shaft 19 rotatable by any suitable source of power. A clutch 20, of any suitable type, is arranged on the shaft 13 in order to control the rotation of the drum 1 as desired.

45 The drum 1 is provided with a head 21 which is apertured at the center thereof to provide a projecting hub 22 in which is rotatably secured one end of an inlet pipe 23 which has its other end suitably connected to a means, (not shown), for forcing dry hot air through the hub 22 and

into a hot air pipe 24 which is secured at one end to the said head 21, and at its other end is secured to a spider 25 fixed to the other end of the drum 1.

The hot air pipe 24 is cylindrical and has its axis coaxial with that of the drum 1. The pipe 24 is provided with a series of slots 26 extending lengthwise thereof and spaced apart. About midway of the pipe 24 a stop plate 27, (see Figure 3), is fixed to block the passage of dry hot air throughout the length of the pipe 24. This plate 27 is provided with an annular flange 28 by means of which the plate 27 may be secured, as by set screws 29 and 30 in any desired position of adjustment lengthwise of the pipe 24.

The outside of the pipe 24 has a large disc 31 secured thereto and about in radial alignment with the stop plate 27 on the inside of the pipe 24. The outer periphery of the disc 31 extends about half way between the outer periphery of the pipe 24 and the inner periphery of the drum 1. Any suitable means may be employed to secure the disc 31 in position perpendicular to the pipe 24. As shown in the drawings, this securing means comprises a comparatively large hollow washer 32 which may be fixed in any desired position of adjustment on the pipe 24 by means of the set screws 33 and 34 (see Figure 4).

With short drums the roller bearings for the drum may be omitted and the pipe 24 may be extended through the hub 35 of the spider 25, and this hub may be used as a trunnion journaled in a bearing 36 which is supported by suitable standards on a base plate 37, as shown in Figure 1. However, where the turnings are large, and the drum correspondingly large, it is preferable to use as many of the roller bearing supports as may be necessary to support the drum rotatably throughout its length.

The turnings may be introduced into the drum 1 from a supply hopper 38 through a door 39 suitably formed in the periphery of the drum 1; and the dry and polished turning may be discharged through the same door 39 into a discharge hopper 40 suitably located at the lower part of the drum.

The stop plate 27 forms a baffle for the hot dry air and forces the air out radially of the pipe 24 through the slots 26. The disc 31 also forms a baffle to confine the air projected through the slots 26 so that it must pass radially toward the periphery of the drums through all the turnings which are rotating about the pipe 24. This means that the air on the inlet side of the disc 31 has its pressure built up sufficiently to force the air

95

throughout all the turnings both radially and lengthwise, and it cannot escape lengthwise of the drum without also passing lengthwise through the turnings.

5 The open end of the drum provided by the spider 25 allows the ready escape of the saturated air. However, this end may be closed and the saturated air conducted from the end of the bearing 36 to any suitable exhaust pipe 41.

10 It will be understood of course that the slots 26 are formed throughout the length of the pipe 24 and that the position of the stop plate 27 and the disc 31 will depend upon the length of the turnings to be dried and polished.

15 What I claim is:

Drying apparatus comprising an imperforate

rotary drum having a head fixed to one end thereof and having an air conduit at the center of said head, means for rotating said drum, a slotted pipe supported within said drum by the ends thereof and coaxial therewith, means for forcing air through said conduit into said pipe, a baffle plate adjustable in said pipe for deflecting air through the slots thereof, a baffle disc adjustable along the outside of said pipe and extending perpendicularly thereto, means for locking said plate in adjusted position in said pipe, and means for locking said disk in adjusted position on said pipe.
